United States Patent Office

Des. 205,566

Patented August 16, 1966

205,566

LETTER TRAY OR THE LIKE

Leo F. Wildgen, Minneapolis, Minn., assignor to Standard Packaging Corporation, New York, N.Y., a corporation of Virginia

Filed Oct. 15, 1965, Ser. No. 87,499

Term of patent 14 years

(Cl. D74—9)

FIG. 1

FIGURE 1 is a perspective view of a letter tray or the like, showing my new design;

FIGURE 2 is an end elevational view thereof, the end opposite thereto being similar in appearance; and

I claim:

The ornamental design for a letter tray or the like, as shown and described.
